UNITED STATES PATENT OFFICE.

CLARENCE M. CHAPMAN, OF TERRYVILLE, CONNECTICUT, ASSIGNOR TO THE CHAPMAN MACHINE COMPANY, OF TERRYVILLE, CONNECTICUT, A CORPORATION OF CONNECTICUT.

ELECTRICALLY-HEATED IMPLEMENT HANDLE.

Application filed March 31, 1926. Serial No. 98,674.

This invention relates to details of the construction of electrically heated soldering implements.

The object of the invention is to so design, construct and correlate the parts that while the copper point may be raised to the required high temperature the total length of the implement may be made much shorter than is possible with the common types of soldering implements and thus it may be more easily and exactly handled and manipulated in use, the parts of the implements being rugged, thoroughly protected, easily assembled and readily renewable in case of necessity, and the handle and shank secured together in such manner that there can be no turning of one in relation to the other.

This object is attained by winding the properly insulated heating coil upon a core consisting of a substantial mass of metal of good heat conductivity and attaching the copper point directly to the outer end of this core, that is, the end of the core that is furthest from the handle, and thus immediately conducting the heat from the heating element in a direction away from the handle, which heating element, comprising the core and resistance coil, is enclosed within a sleeve having a tubular shank that extends into a metallic bushing which is inserted into and heat insulated from a metallic ferrule that is concealed in the handle of heat non-conducting material. The binding screws for the leads that pass through the tubular shank to the resistance coil and the binding screws for the terminals of the circuit wires that enter through the handle are mounted upon a flexible support that is attached to the inner end of the tubular shank. As the heat is conducted directly to the point away from the handle and as the tubular shank is insulated from the handle and cannot turn in relation thereto the shank can be shorter and the handle much nearer to the point than is usual, thus providing a tool that is more easily handled than the much longer tools in common use.

In the accompanying drawings Fig. 1 is

a side view of a soldering implement that embodies the invention. Fig. 2 shows on a larger scale a side view of the copper point and the metallic core to which the point is attached, the heating coil on the core and the enclosing sleeve being in section. Fig. 3 is a similar view showing in section a core of different shape, such for instance as may be used with a point of larger size than the one illustrated in Fig. 2. Fig. 4 is a longitudinal section of the handle, showing the handle end of the tubular shank and the circuit terminal strip in side view. Fig. 5 is a similar view looking at the edge of the terminal strip and with the tubular shank in section. Fig. 6 is a transverse section on the plane indicated by the dotted line 6—6 on Fig. 4.

In the forms illustrated in the drawing the copper point 1 has a stem 2 that is screwed into the flanged head of the core 3 of the heating element, thus the points while removable and interchangeable have a close and extended contact with the core. The core is a substantial piece of metal of good heat conductivity and it may be cylindrical as shown in Fig. 2 or conical as illustrated in Fig. 3. The outer end of the core against which the point sets, has a head 4 and at the inner end the core has a flange 5 that has a diametrical slot 6 with rounded corners. Extending inward from the inner end of the core is a pin 7 which may be, to an extent, flexible. The heating coil of resistance wire 8 having the required turns and suitably insulated is wound upon the core between the head and the flange, and its terminals are passed through the slot in the core flange and led along and bound to the pin.

Enclosing the heating unit and fitting the head and also the flange of the core is a sleeve 9 that has a tubular shank 10. The sleeve may be pinned to the head to prevent the core from turning when the point is screwed in. The sleeve may be cylindrical as shown in Fig. 2 or conical as illustrated in Fig. 3. The handle 11 of wood or other

suitable heat insulating material has a central bore 12. Driven into an annular mortise in the point end of the handle, preferably so as to be completely concealed in the handle, is a metallic ferrule 13, and driven into the bore within the ferrule is a metallic bushing 14. The exterior surface of the bushing is roughened so as to prevent it from turning when once driven in, see Fig. 6. The ferrule prevents the handle from splitting, and the bushing being heat insulated from the ferrule by a section of the handle the flow of heat from the bushing to the ferrule and outer surface of the handle is prevented. The outer end of the bushing has a socket 15. Near its inner end the tubular shank has a collar 16, which when the end of the shank is inserted into the bushing, enters the socket. A screw 17 may be passed through the socket wall into the collar to hold the shank from turning and removal.

Attached to the inner end of the shank is a flexible metallic strip 18 to the faces of which strips of insulation 19 are fastened. On one side of this composite terminal strip are binding screws 20 connected by a conducting plate 21, and on the other side are binding screws 22 connected by a conducting plate 23. This terminal strip is secured to studs 24 that are fastened to the inside of the tubular shank by binding screws 25. Fig. 5. The terminals of the heating coil leads may be led through the shank and fastened to the nearest screws on each terminal block, while the other screws are designed to be used for fastening the terminals of the circuit wires.

The parts of this tool are cheaply formed and readily assembled. The points may be removed and others substituted in case one of a different size is desired or when one becomes incapacitated through long use. The heating coil is thoroughly protected and yet can be readily removed and another substituted in case it becomes ineffective for any cause. The terminals of the heating coil and the circuit wires can be easily connected or disconnected as desired for, by removing the screw 17 the handle with the bushing 14 and its socket 15 is free to be withdrawn from the shank 10 and its collar 16 so as to expose the binding screws on the strip which is attached to the shank. As the core consists of a substantial body of metal and as the point is directly applied to the outer end of this core and has large surface contact therewith, the heat developed by the heating coil is conducted by this mass of core directly to the point where it is desired, and this flow of heat is away from the handle, thus permitting the handle to be brought closer to the point than is usual. Furthermore the handle as attached will not turn on the shank and it is protected from splitting, and also from being burned, by the concealed ferrule which is insulated from the other metal parts. Therefore the handle not

only can be nearer to the point, but when thus constructed it does not become loose on the shank, nor has it any exposed parts which are in contact with metallic parts that become hot, so that there is no danger of the user accidentally burning his fingers by accidentally touching such parts, for instance, as is the case with tools which have a protecting ferrule on the outside, and is in direct contact with some of the metal parts that are heated when the tool is in use.

The invention claimed is:—

1. A handle for an electrically heated implement, said handle comprising a body of heat non-conducting material and having a central bore with a metallic bushing held against rotation in one end of said bore and adapted to detachably receive the end of the implement shank, said handle body also having an embedded and unexposed metallic ferrule surrounding but separated from said bushing whereby the metallic strengthening ferrule is heat insulated from the bushing and from the outer surface of the handle.

2. A handle for an electrically heated implement, said handle comprising a body of heat non-conducting material and having a central bore, with a metallic bushing held against rotation in one end of said bore, said bushing having a socket at the outer end of the bushing, adapted to detachably receive the end of the implement shank and a collar attached thereto, said handle body also having an embedded and unexposed metallic ferrule surrounding but separated from said bushing whereby the metallic strengthening ferrule is heat insulated from the bushing and socket, also from the outer surface of the handle.

3. A handle for an electrically heated implement, said handle comprising a body of heat non-conducting material and having a central bore with a metallic bushing held against rotation in one end of said bore, said bushing having a socket at the outer end of the bushing, a tubular implement shank with a collar thereon, detachably fitted into said bushing and socket, means detachably fastening said collar in said socket, and an unexposed metallic ferrule surrounding but separated from said bushing, embedded in the end of the handle body whereby the metallic strengthening ferrule is heat insulated from the bushing, the socket, the shank, and the outer surface of the handle.

4. A handle for an electrically heated implement, said handle comprising a body of heat non-conducting material and having a central bore, with a metallic bushing held against rotation in one end of said bore, said bushing having a socket at the outer end of the bushing, a tubular implement shank with a collar thereon, fitted into said bushing and collar, a circuit terminal strip with binding screws attached to and projecting from the end of said shank in the bore, and an unex-

posed metallic ferrule surrounding but separated from said bushing, embedded in the end of the handle body.

5. A handle for an electrically heated implement, said handle comprising a body of heat non-conducting material and having a central bore, with a metallic bushing held against rotation in one end of said bore, said

bushing having a socket at the outer end of the bushing, adapted to receive the end of the implement shank and a collar attached thereto, a flexible metallic terminal strip attached to the end of the shank within said bore, insulating pieces facing said strip with binding screws on opposite sides of said facing strips.
